1

For ultra-short wave purposes use is frequently made of oscillatory circuits which substantially consist of a system of two parallel conductors, which conductors either are placed side by side or again are formed as concentric conductors.

For altering the tuning frequency of such oscillatory circuits it is known to utilize a tuning bridge which is slideable along the conductor system and which forms a short-circuit for oscillations whose frequency corresponds to the natural frequency of the system. The movement of the tuning bridge is preferably effected in this case by means of a threaded shaft.

It has been found, however, that it is difficult to tune these known tunable oscillatory circuits very exactly for very short waves, for example, if the wave length is of the order of magnitude of 10 cms. since even a very slight displacement of the tuning bridge, for example a displacement of about 0.01 mm. brings about a comparatively great variation of the tuning frequency. As a result, great practical inconveniences are encountered in the mechanical constructions of the tuning mechanism.

These drawbacks may be obviated by utilizing, in accordance with the invention, an oscillatory circuit which comprises two bridge pieces of which at least one is slideable along the conductor system whilst the two bridge pieces are coupled with a common tuning member and, when the latter is being operated, are moved with respect to the tuning member in the longitudinal direction of the conductor system in the same direction and at different speeds.

The tuning member preferably comprises a shaft which exhibits two threaded parts both of which are mechanically coupled with the tuning bridges respectively and have screw-threads whose pitches have the same direction but different values.

When the invention is carried into effect, the length of that part of the conductor system which determines the natural frequency of the circuit, undergoes a change which corresponds to the disparity in displacement of the two bridge-pieces with respect to the tuning member. The manufacture of the tuning mechanism, for example the production of the said screw-threads, which, in themselves, may have a comparatively large pitch, does not entail grave practical inconveniences whilst a sufficient accuracy of tuning may be ensured in the case of very short waves, for example of 10 cms.

The invention will be explained more fully with reference to the accompanying drawing which

2

represents, by way of example, two forms of construction of tunable oscillatory circuits according to the invention.

Fig. 1 represents an oscillatory circuit according to the invention which substantially consists of two conductors arranged side by side and parallel to one another, whilst

Fig. 2 represents an oscillatory circuit according to the invention which comprises two concentric conductors.

In Fig. 1, 1 and 2 denote conductors which are arranged side by side and parallel to one another and which, jointly with bridge pieces 3 and 4, form an oscillatory circuit. The bridge-pieces 3 and 4 are slideable with respect to the conductors 1 and 2 and may be displaced with the aid of a tuning shaft 5 provided with an operating knob 6. The coupling of the oscillatory circuit with the other elements of the circuit arrangement in which the oscillatory circuit is utilized, may be brought about, for example, by means of a coupling loop 9 provided with connecting terminals 10, said loop being stationary with respect to the conductors 1 and 2.

The tuning shaft comprises two threaded parts 7 and 8 of substantially equal length which, when the knob 6 is being turned, move the bridge-pieces 3 and 4 respectively with respect to the conductors. The pitches of the screw threads 7 and 8 have the same direction but different values so that the relative displacement of the bridge-pieces and therefore the variation of the natural frequency of the oscillatory circuit is determined by the difference in value between the pitch of the screw thread 7 and that of the screw thread 8. The screw thread 7 exhibits, for example, nine and the screw thread 8 ten threads per cm., in which event upon ten revolutions of the operating knob the change in length of the oscillatory circuit conductors is only about 1 mm. and consequently with very short waves an exact tuning can be ensured without practical drawbacks being encountered in the production of the screw thread.

In order to prevent the oscillatory circuit from being influenced by the tuning shaft, the latter is preferably made of insulating material.

In order to avoid backlash of the tuning mechanism due to the play which may occur between the screw threads 7, 8 and the bridge-pieces 3, 4, it is advantageous to utilize means known per se in order to avoid such a play. For this purpose use may be made, for example, of helical springs which are secured at one end to the shaft 5 and at the other end to a bridge-piece and which

thus exert on the latter a force which is axially directed.

In the above it is tacitly assumed that the two bridge-pieces are slidable with respect to the conductor system and that the shaft 5 cannot be displaced in the longitudinal direction of the conductors. It is, however, also possible to arrange that one of the two bridge pieces and the shaft 5 are slidable with respect to the fixed conductors 1, 2 without departing from the essence 10 of the present invention as will be set out more fully with reference to Fig. 2.

The oscillatory circuit according to Fig. 2 comprises two concentric conductors 11 and 12 whilst at the two ends are provided bridge-pieces 13 and 14. The bridge-piece 13, which galvanically connects the conductors to one another at one end, is rigidly connected to the conductors and preferably has a circular shape so that the space between the conductors is closed. The bridge-piece 14 is mounted so as to be slidable with respect to the conductors and exhibits a circular hole through which passes the inner conductor 12 whilst the outer circumference preferably also has a circular shape. In order to ensure a satisfactory contact along the whole inner and outer circumferences of the bridge-piece 14 with the conductors, it is advantageous, as is known in itself, to utilize resilient contact strips which are provided on the inner and outer circumference respectively.

At the end remote from the bridge-piece 13 the space between the conductors is closed by a circular plate 15 but which plate may also be omitted as one versed in the art can readily appreciate from the Fig. 1 embodiment of this invention.

The outer conductor 14, which, in the form of construction according to Fig. 2 acts at the same time as a screening envelope, is provided with two slots 16, 17 which are provided diametrically opposite one another and which extend in the axial direction of the conductors. Two projections of the tuning bridge 14 project through the said slots to the outside. The slots serve to guide the bridge-piece and prevents the latter from rotating. To the projections of the bridge 14 are secured the ends of two rods 18 and 19, preferably of insulating material, which are symmetrically arranged with respect to the oscillatory circuit and which are secured at the other ends to a transverse connecting piece 20 which is provided with a threaded hole. This screw thread corresponds to that part of a tuning shaft 22 which has a screw thread 21, said shaft being provided with an operating knob 23 with the aid of which the bridge-piece 14 may be displaced with respect to the conductors 11, 12. Owing to the symmetrical construction of the tuning mechanism any torsion of the bridge 14 in the outer conductor when the latter is being displaced is avoided.

By turning the tuning shaft 22 the bridge-piece 14 is moved relatively to the said shaft. However, by turning the shaft 22, the latter is also displaced in its longitudinal direction relatively to the oscillatory circuit 11, 12 with the aid of a second part of the shaft, which part is provided with a screw thread 24 and is journalled in a part of the hollow inner conductor 12 which is provided with a screw thread 25.

Since here again the pitches of the screw threads 21 and 24 have the same direction but different values, the displacement of the tuning bridge 14 relatively to the conductors 11 and 12 is determined, as in Fig. 1, by the disparity in relative displacement of the parts 14 and 22

and the parts 22 and 12 respectively, owing to which exact tuning of the oscillatory circuit is ensured.

In the forms of construction represented by way of example, the length of the conductor system corresponds to one-half wavelength of oscillations with a natural frequency of the circuit, which in itself is advantageous with very slight wavelengths since in this case the length of the oscillatory circuit conductors does not become too small.

Upon carrying out the invention for wavelengths with which from a mechanical point of view the slightest possible length of the conductor system is allowable, the length of each of the oscillatory circuit conductors preferably corresponds to a quarter wavelength. When the invention is carried into effect, one of the bridge-pieces should consist in this case of insulating material and exclusively forms of construction fundamentally similar to that of Fig. 2 may, of course be utilized.

We claim:

1. A tunable oscillatory circuit comprising an inner and an outer conductor fixedly connected together at one end by an end plate so as to constitute a concentric line resonator, a metallic bridge piece connecting the outer surface of the inner conductor with the inner surface of the outer conductor for tuning said oscillatory circuit, a shaft having two spaced screw threads of different pitches, said shaft entering the interior of said inner conductor, one of said screw threads engaging said inner conductor for causing movement of said concentric line resonator as an integral unit, the other of said screw threads on said shaft being linked to said bridge piece, whereby rotation of said shaft causes both said resonator and said bridge piece to move simultaneously in the same direction but at different rates.

2. A tunable oscillatory circuit comprising an inner conductor with an interiorly threaded end, an outer conductor with opposed slots concentric with said inner conductor, means fixedly coupling said conductors respectively at each end to produce a resonator, movable bridge means with projections mating said slots for connecting and guiding the outer surface of the inner conductor with the outer conductor for tuning said oscillatory circuit, a centrally located transversely threaded connecting piece, rod means coupling said movable bridge means with said connecting piece, a shaft with spaced groups of threads of different pitches threaded into said connecting piece and said inner conductor whereby rotational movement of said shaft causes relative motion between said resonator and said bridge means.

3. A tunable oscillatory circuit comprising an inner and an outer conductor fixedly connected together at one end by an end plate and at the other end by a first bridge piece so as to constitute a concentric line resonator, a second metallic bridge piece connecting the outer surface of the inner conductor with the inner surface of the outer conductor for tuning said oscillatory circuit, a shaft having two spaced screw threads of different pitches, said shaft entering the interior of said inner conductor, one of said screw threads engaging said inner conductor for causing movement of said concentric line resonator as an integral unit, the other of said screw threads on said shaft being linked to said second bridge piece, whereby rotation of said shaft causes both

said resonator and said second bridge piece to move simultaneously in the same direction but at different rates.
